HOLDER FOR LIPSTICK TUBES

Samuel E. Kelman, Providence, R.I., assignor to The Metalart Company, Providence, R.I., a corporation of Rhode Island

Filed Jan. 16, 1961, Ser. No. 63,570

Term of patent 3½ years

(Cl. D86—10)

Fig. 1

Fig. 2

Fig. 3

Fig. 4

Fig. 5

Fig. 6

FIG. 1 is a side elevational view of a holder for lipstick tubes showing my new design;

FIG. 2 is an end view as seen from the right of FIG. 1;

FIG. 3 is a top plan view thereof;

FIG. 4 is a view of the opposite end from that shown in FIG. 2;

FIG. 5 is an elevational view of the opposite side from that shown in FIG. 1; and

FIG. 6 is a bottom plan view thereof.

I claim:

The ornamental design for a holder for lipstick tubes, substantially as shown.
